UNITED STATES PATENT OFFICE.

DEWARD J. PETERSON, OF GREENVILLE, WISCONSIN.

STRAINING MEANS.

1,237,809.

Specification of Letters Patent. Patented Aug. 21, 1917.

Application filed July 1, 1916. Serial No. 107,127.

To all whom it may concern:

Be it known that I, DEWARD J. PETERSON, a citizen of the United States, residing at Greenville, in the county of Outagamie and State of Wisconsin, have invented certain new and useful Improvements in Straining Means, of which the following is a specification.

This invention relates to straining means, and more particularly to means adapted for use in connection with dairying operations for straining milk.

One of the main objects of my invention is to provide means of simple construction and operation for straining milk by applying pressure to the same. A further object is to provide means of the character stated by which a straining element of very fine texture may be utilized so as to remove all foreign matter from the milk. Further objects will appear from the detailed description.

In the drawings:—

Figure 1 is a side view of the invention, Fig. 2 is a vertical sectional view through the strainer vessel,

Fig. 3 is a section on line 3—3 of Fig. 1, and

Fig. 4 is an underneath view of the strainer.

The strainer vessel or container A has a cylindrical body portion 1, a reduced lower portion 2, and an intermediate portion 3 of inverted frusto-conical shape connecting the body portion and the lower portion. The body portion 1 is provided, near its upper end, with an inwardly projecting peripheral flange 4. A cover 5 fits snugly into the upper end of vessel A and is provided with an outwardly projecting peripheral flange 6 which fits tightly against the upper edge of the vessel. The top 7 of the cover is connected to flange 6 by a vertical peripheral wall 8 of such length as to bring the under face of the top 7 of the cover within a short distance of the upper face of flange 4. A packing ring 9 of soft rubber or other suitable material, is mounted on flange 4 between the same and the cover, and is adapted to effect a fluid tight closure between the strainer vessel and the cover when the cover is in operative position.

A bail 10 is loosely mounted on each side of the vessel A in ears 11 secured thereto. These bails have their ends bent at right angles, as at 12 so that, when turned inward,

their body portions will be above and parallel with the top 7 of the cover. When the bails have been turned inward their adjacent ends are secured together by means of a clip 13, the ends of which are turned downward at right angles to engage the bails. This clip is provided at its center with a semi-circular recess 13^a to fit about the nipple 14 threaded through the cover 5 at the center thereof. A collar 15 is slidably mounted on the nipple 14 and is secured in adjustment thereon by means of a set screw 16. A pressure block 17 is loosely mounted about the nipple 14 above collar 15, and has its ends turned upward and oppositely beveled, as at 18. By turning this block under the inner ends of the bails the beveled surfaces 18 are brought into engagement with the under surfaces of the bails 75 and act to force the cover 5 downward, thus securing it firmly in position and effecting a tight closure between the cover and the upper end of the vessel A. The amount of pressure exerted by the block 17 can be varied by adjusting the collar 16, as will be evident, so that proper allowance may be made for any wear of the packing ring 9.

The lower reduced portion 2 of vessel A is provided, near its lower end, with an inwardly projecting annular flange 19. Two diametrically opposite ears 20 are secured to the lower portion 2 of the vessel and are bifurcated to receive the vertical arms of angle clamps 21. The upper ends of the vertical arms of clamps 21 are pivoted to eccentric levers 22 rockably mounted in recesses in the upper edges of the ears 20. The horizontal arms of the angle clamps 21 engage a circular wire frame 23 which fits snugly in the lower end of the portion 2 and has a wire gauze screen 24 secured thereon. A piece of felt 25 or other suitable fibrous material of fine texture is placed above the frame 23, and a packing ring 26 of cork, or other suitable material, is placed above the straining element 25 and below the flange 19. By suitably rotating the eccentric levers 22 the screen 24 is forced upward so as to effect a tight closure between the felt 25 and the flange 19, thus making a liquid tight closure between the lower end of the vessel A and the strainer. A strap 27 is secured about the body of vessel or container A and provided with integral arms 27^a adapted to be secured to a wall 28 or other suitable support.

A tank 29 is mounted above the container A and is connected to the nipple 14 by a flexible tubing 30. This tank is adapted to contain compressed air, or other suitable pressure fluid, supplied thereto by a pump or other form of air compressor. The flow of the air from the tank 29 to the container A is controlled by the valve 31.

A can 32 is mounted below the container A with its open upper end closely adjacent to strainer 24.

In using the invention, the cover 5 is removed and a sufficient quantity of milk poured into the container A so as to fill the same to within a short distance of the flange 4 at the upper end thereof. The cover is then replaced and firmly secured in position, after which the valve 31 is turned so as to admit air from tank 29 into the upper end of the container, above the column of liquid therein. The air acts to force the milk through the strainer, composed of the felt piece 25 and the gauze 24, so as to effectually strain the same. The gauze 24 acts to support the felt, and the felt prevents all particles of dirt or foreign matter from passing through with the milk, thus insuring a thorough and proper straining of the milk. By this means the milk may be very quickly strained and, at the same time, all small particles of dirt are removed from it. After the straining has been completed, the cam levers 22 may be turned up so as to release the circular wire frame 23, after which the felt 35 may be quickly and easily removed for washing or for inserting a new piece of felt.

There may be slight changes made in the construction and disposition of the various parts of the invention without departing from the field and scope of the same, and I intend to include all such variations as fall within the appended claims, in this application, in which a preferred form only of the invention is disclosed.

45 What I claim, is:—

1. In straining means, a receptacle having an inner annular flange adjacent its upper end, a straining medium removably secured in the lower end of said receptacle, a closure member fitting snugly into the upper end

of the receptacle, said member being provided with an upwardly extending annular flange and an outwardly extending flange integral therewith, said flanges being adapted to fit into and about the upper portion of the receptacle so as to effect a tight closure therewith, a pair of oppositely disposed bails loosely secured to the receptacle and positioned to fit inward across the closure member, a clip connecting the said bails, a nipple threaded into the closure member at the center thereof, and a pressure block rotatable about said nipple, said block having its end turned upward and oppositely beveled to form cam faces for engagement with said bail so as to force the closure member downward tightly into the receptacle when said block is rotated in one direction about the nipple.

2. In straining means, a receptacle having an inner annular flange adjacent its upper end, a straining medium removably secured in the lower end of said receptacle, a closure member fitting snugly into the upper end of the receptacle, said member being provided with an upwardly extending annular flange and an outwardly extending flange integral therewith, said flanges being adapted to fit into and about the upper portion of the receptacle so as to effect a tight closure therewith, a pair of oppositely disposed bails loosely secured to the receptacle and positioned to fold inward across the closure member, a clip connecting the said bails, a nipple threaded into the closure member at the center thereof, a pressure block rotatable about the said nipple, said block having its ends turned upward and oppositely beveled to form cam faces for engagement with said bails so as to force the closure member downward tightly into the receptacle when said block is rotated in one direction about the nipple, and means for adjusting the said pressure block vertically on said nipple.

In testimony whereof I affix my signature 95 in presence of two witnesses.

DEWARD J. PETERSON.
